UNITED STATES PATENT OFFICE.

WILLARD N. SAWYER, OF WINCHENDON, MASSACHUSETTS, ASSIGNOR TO BAXTER D. WHITNEY & SON, INC., OF WINCHENDON, MASSACHUSETTS, A CORPORATION OF MASSACHUSETTS.

WOODWORKING MACHINE.

Application filed August 8, 1924. Serial No. 730,803.

To all whom it may concern:

Be it known that I, WILLARD N. SAWYER, a citizen of the United States, residing at Winchendon, in the county of Worcester and State of Massachusetts, have invented an Improvement in Woodworking Machines, of which the following description, in connection with the accompanying drawings, is a specification, like characters on the drawings representing like parts.

This invention relates to wood working machines of the type employing a rotating cutter which acts upon the work in conformity with the curvature of different patterns. In machines of this type the work is secured to a pattern having the desired configuration, and is then moved into engagement with the cutter and is advanced relative to the cutter while the pattern engages a pattern guide.

The present invention relates to various improvements in this type of machine by which the work may be readily presented to and removed from the cutter, and by which the work is held firmly in place during the cutting operation and is advanced relative to the cutter by power-operated means.

One important feature of the present invention resides in an element supported near the cutter and adapted to exert a substantial downward pressure upon the work and pattern to maintain the work in firm engagement with the pattern, and which prevents the work from lifting up under the action of the cutter.

Another feature of the invention resides in means for moving the work to the operative position and for holding the work firmly in place against the cutter during the cutting operation, and in power operated means for feeding the work relative to the cutter.

Another feature of the invention resides in novel means for rotating the work relative to the cutter and which is constructed so that the work may be freely moved toward and from the cutter without disengaging the driving connections between the work and source of driving power.

Another feature of the invention resides in

foot controlled means for facilitating removal of the work from the cutter, and in latch means for automatically holding the parts in the inactive position while one piece of work is being removed from the machine and another piece is being placed on the machine.

Other features of the invention and novel combination of parts in addition to the above will be hereinafter described in connection with the accompanying drawings, which illustrate one good practical form thereof.

In the drawings—

Fig. 1 is a perspective view of a wood-working machine embodying the features of the present invention.

Fig. 2 is a side view of the machine of Fig. 1 with the table and associated parts shown in section and disclosing the rotating cutter at the right hand side of the machine.

Fig. 3 is an enlarged top plan view of Fig. 1 showing the cutters in operation upon different types of work.

Fig. 4 is an enlarged sectional view of parts shown in Fig. 2.

Fig. 5 is a plan view of a portion of the machine of Fig. 1 provided with a different construction for rotating the pattern relative to the cutter, the pattern and work being omitted.

Fig. 6 is a vertical sectional view taken on line 6—6 of Fig. 5 with the work in place, and;

Fig. 7 is a plan view of a portion of the machine of Fig. 1, provided with still another construction for rotating the pattern and work.

The machine of the present invention is designed to cut edges and marginal portions of the work, in conformity with any desired pattern, and in Fig. 1 one cutter is shown as operating upon the outer edge of a toilet seat to give the same the desired configuration, while the work has been removed from the other cutter to show the means of the present invention for holding the work in engagement with the cutter, and in Fig. 3 one of the cutters is shown as operating upon

the toilet seat of Fig. 1, and the other cutter is shown as operating upon the cover of a toilet seat. It will be understood, however, that the present machine will operate satisfactorily upon straight or curved surfaces, as well as the substantially circular work shown.

The wood working machine illustrated is provided with a supporting frame, consisting of a base 10 having an upwardly extending column 11, at the upper end of which is provided the work supporting table 12. The present machine, as usual, is provided with two different cutter units, one of which rotates its cutter in a right-hand direction, and the other rotates its cutter in a left-hand direction, to avoid operation of a cutter against the grain of the wood, and it is customary to present one side of a piece of work to a cutter rotating in one direction and the other side of the work to a cutter rotating in the opposite direction, thereby avoiding the operation of a cutter against the grain of the wood. This is not always necessary, however, because, if the cutter is driven at a high speed and the work is fed smoothly and gradually towards the cutter, the cutting operation will be performed properly, irrespective of the direction in which the grain runs. The cutter units and means for operating the same may be similar, except that, as above stated, one cutter is rotated in a right-hand direction and the other in a left-hand direction.

In the embodiment of the invention illustrated, it is assumed that the cutter 13 is rotated in a clockwise direction. This cutter is rigidly secured by means of a nut 14 to a vertical operating shaft 15, which shaft extends upwardly thru an opening in the table 12, and the shaft 15 is conveniently driven by an electric motor 16, mounted for vertical sliding movement upon slide-ways 17. It is desirable to provide means for raising and lowering the shaft 15 so that the cutter may be raised or lowered to accommodate different work upon the table 12, and to this end, in the present case, the motor casing is provided with a laterally extending lug 18 having a threaded opening adapted to receive the threaded shaft 19 journaled in a bearing 20 supported by the machine frame. This threaded shaft may be rotated by a hand wheel 21 rigidly secured to a laterally extending shaft 22 and rotative movement is imparted from the shaft 22 to the threaded shaft 19 by bevel gears enclosed within the casing 23. The arrangement is such that the hand wheel 21 may be rotated in one direction to operate the threaded shaft so that it will raise the cutter 13, and in an opposite direction to lower this cutter.

It is assumed that the second cutter 24 is rotated in a contra-clockwise direction

and this cutter is rigidly secured to a vertical shaft 25 which extends upwardly thru an opening in the table 12 and is rotated by an electric motor 26 similar to the shaft 15, and the cutter 24 may be raised or lowered by a threaded shaft 27 which may be rotated by the hand wheel 28, similar to the manner in which the threaded shaft 19 is rotated.

In Fig. 1 of the drawing, the cutter 24 is shown as operating upon a toilet seat 29 which is rigidly secured to a pattern 30, the outer edge of which has the configurations it is desired to impart to the work 29. The work may be secured to the pattern 30 by various means, and, in the present case, this is accomplished by a bridge bar 31 mounted upon a stem 32 extending upwardly from the pattern 30, and the upper end of this stem is provided with any desired form of clamping means 33.

The present invention contemplates mechanism for moving the work into the cutter-engaging position, and, in the present case, this is accomplished by means of a slide 34 mounted in a slot 35 formed in the table 12 for movement towards and from the cutter-operating shaft 15, it being understood that a similar slide 34 and operating means for the same is provided adjacent the cutter 24. Each slide is urged toward its cutter by a cable 36 the inner end of which is secured to a post 37 projecting downwardly from the under face of the slide (see Fig. 2), and the cable passes about one pulley 38 that rotates in a horizontal plane and about a second pulley 39 that rotates in a vertical plane, and the downwardly extending portion of the cable 36 is provided with one or more weights 40.

The pattern 30 is shown as having a relatively large central opening surrounded by the inner wall 41 and the slide adjacent the cutter 13 is provided with a transversely extending bridge 42 secured to the slide by a bolt 43, and upon the upper face of the bridge 42 are mounted the spaced rollers 44 journaled upon the upstanding posts 45. The arrangement is such that the rollers 44 engage the inner curved face 41 of the pattern at spaced points and act upon the pattern to move it and the work 29 towards the cutter. It is apparent that a single roller might be provided in place of the two spaced rollers shown, but the laterally spaced rollers are desirable because they exert a feeding pressure upon the pattern at points disposed at each side of the cutter to steady the work.

During the cutting operation it is necessary that means be provided for guiding the pattern as the work is fed relative to the cutter, and this guide, in the embodiment of the invention shown, consists of a rub roll 46 concentric with the vertical shaft 15, and

mounted upon a sleeve 47 which sleeve surrounds the shaft 15 and is rotatably mounted in a removable portion 48 of the table 12.

Means is provided for advancing the work 5 relative to the cutter while the work is held against the cutter by the slide 34 in the manner just described, and to this end the outer periphery of the pattern 30 is provided with a rack or perforated band 49 adapted to mesh with the teeth of a gear 50 mounted upon and rigidly secured to the sleeve 47. Means is provided for rotating the sleeve 47 and gear 50 at a relatively slow speed, as compared to the speed of the shaft 15, and, in the construction shown in Figs. 1 to 4 inclusive, this means consists of the gear 51 rigidly secured to the sleeve 47 at the under face of the table and this gear is driven by a gear 52 rotatably supported at the under face of the table, and the gear 52 is in turn driven by a gear 53. The gear 53 is driven by the worm wheel 54, and the worm wheel for driving the feed means for the cutter 13 meshes with a 25 worm 55 upon a horizontally extending shaft 56, while the worm wheel for driving the feed means for the cutter 24 is rotated in the opposite direction by the worm 55^a upon the shaft 56. The shaft 56 may be driven 30 by a cone pulley 57.

From the construction described so far, it will be seen that during the cutting operation the work 29 is held in engagement with its cutter, and, the outer edge of the pattern 30 is held in engagement with the rub roll 46 by the pressure of the slide 34 acting under the influence of the weight 40, and that, as the gear 50 which meshes with the rack 49 is rotated by the chain of gears described, the work will be fed positively and smoothly past the cutter, and it will be seen that the work will be advanced in the manner just described until the cutting operation has been formed entirely around 45 the toilet seat 29, whereupon this particular piece of work may be removed by the attendant in charge of the machine and another piece of work presented to the cutter.

The weight 40 should be relatively heavy 50 in order to hold the pattern against the pattern guide or rub roll 46 with substantial pressure, and, as a result, a substantial amount of force is required to withdraw the slide 34 from its inner position, when 55 the work is to be removed from the cutter. The present invention, therefore, contemplates means for withdrawing the slide 34, which may be easily operated by the machine attendant's foot, and to this end 60 a lever 58 is mounted below the table 12 in approximately a vertical position and is pivotally secured between its ends to a bracket 59 by a pivot pin 60. The lower end of the lever 58 is disposed near the 65 base of the machine and is provided with a

foot treadle 61 upon which the machine attendant may readily place his foot to force the lever in an inward or right-hand direction, viewing Fig. 2. This serves to rock the upper portion of the lever 58 outwardly 70 and at the upper end of the lever is provided a dog 62 pivoted to the lever at 63 and the outer end of the dog is adapted to engage teeth 64 formed in the lower face of the slide 34. The arrangement is such 75 that as the foot lever 58 is actuated by the pressure of the foot of the machine attendant, the dog 62 will move into engagement with one of the teeth 64, and as the rocking movement of the lever 58 continues the slide 34 will be withdrawn from the cutting position.

The dog 62 is urged toward its operative position by a coiled spring 65 and as the pressure is relieved from the treadle 61 the 80 lever 58 is rocked outwardly under the influence of the spring 66 and, as the parts approach the position shown in Fig. 2, the upper face of the dog 62 engages a fixed surface which forces the dog downwardly 85 out of engagement with the teeth of the slide, as will be apparent from Fig. 2, this allows the slide 34 free movement back and forth, independent of the dog 62.

It is desirable to provide means for maintaining the foot-operated lever 58 in the slide retracted position, without requiring the machine attendant to maintain a pressure upon the foot treadle 61. This is accomplished in the present case by providing a latch 67 pivotally mounted at 68 upon a portion of the lever 58 and, as this lever is moved by the machine attendant to its rearmost position, the inner end of the latch 68 engages a shoulder 69 upon the fixed 90 bracket 59, the latch being moved to this position by the compressed spring 70. While the slide is held in its retracted position by the latch 67 acting upon the lever 58, the pattern 30 may be removed from 95 the slide 34 and another pattern of similar construction, but provided with a piece of work which has not been acted upon by the cutter, may be placed over the slide, or the work 29 may be removed from the pattern 100 105 and another piece of work substituted in its place, without removing the pattern 30 from the table.

The latch 67 may then be operated to release the lever 58, whereupon the slide will 110 be moved inwardly under the action of its weight to move this new piece of work into engagement with the cutter. The means shown for moving the latch 67 out of engagement with the notch 69 consists 115 of a chain 71, one end of which is secured to the latch and the other end is secured to the treadle 61, and this treadle is pivotally mounted upon the lever 58 by a pin 72, so that the treadle may be readily 120 125 130 135 140 145 150 155 160 165 170 175 180

rocked by the machine attendant to thereby exert a pull upon the chain 71 to trip the latch 67 and release the lever 58.

It will be understood that the slide 34 for feeding work to the cutter 24 is provided with means similar to that just described for holding the slide in its retracted position.

In some classes of work the blank to be operated upon cannot be readily clamped to its pattern. This is true in the case of the flat cover for a toilet seat, such as shown in engagement with the cutter 24 in Fig. 3. This cover 73 has no central opening to receive clamping means, but it may be secured to its pattern by providing the latter with small spurs or pins 74 which project into the under face of the cover 73. In this type of work it may not be practical to provide the pattern with a central opening similar to the opening 41 provided in the pattern 30, and as a result the spaced rollers 44 cannot be used with such a pattern. In this case the bridge member 42 may be readily removed by unscrewing the bolt 43 and engagement between the pattern for the cover 73 and the slide 34 may be obtained by providing the pattern with a downwardly extending pin 76, which engages the notch 77 at the inner end of the slide 34. In this construction it will be apparent that the inward feeding pressure of the slide 34 acts upon the pin 76 to force the cover 73 into active engagement with the cutter.

When the pins 74 are relied upon to secure the work 73 to its pattern, there is danger that the cover may work upwardly away from its pattern, under the action of the cutter, and novel means to avoid this will now be described. This means consists of an element supported near the cutter and in spaced relation to the upper face of the table 12 so that the element will exert a substantial downward pressure upon the work and pattern during the cutting operation. In the construction shown, an upstanding post 78 is rigidly secured to the upper face of the table 12 adjacent either cutter by bolting the flange plate 79 at the lower end of this post to the table, and upon the post 78 is mounted a split sleeve 80 which may be clamped in any desired position of adjustment lengthwise of the post by tightening a clamping bolt 81. The sleeve 80 is provided with a laterally extending portion 82 provided with elongated slots 83 adapted to receive the clamping bolts 84. The bolts 84 are adapted to secure an arm 85 rigidly to the portion 82 in different positions of adjustment. The arm 85 carries at its outer end a vertically disposed sleeve 86 in which a plunger 87 is slidably mounted, which plunger is provided at its lower end with a roller 88 adapted to engage the upper face of the work. The roller 88 is of the

universal type that will rotate freely in any direction so that it will roll smoothly upon the work when the latter is given a rotative movement relative to the cutter or is moved laterally toward and from the cutter, and the roller is shown as mounted in a socket having an upwardly extending stem 89 which is secured within the plunger 87 by a set screw. It is desirable that the roller 88 be held in engagement with the work by a yielding, downward pressure, and this is accomplished by confining a spring 90 within a socket formed partly in the upper end of the plunger 87 and partly within an adjustable screw 91, which screw may be rotated to vary the tension of the spring 90. The downward movement of the plunger 87 is limited by a shoulder 92 adapted to engage a cooperating shoulder formed in the sleeve 86, and the upward movement of the plunger may be limited by the nut 93. Altho the means (just described) for maintaining a downward pressure upon the work and pattern is very desirable when there is danger of the work becoming disengaged from the pattern, as in the case of the cover 73, the holding means just described may be used to advantage, even when there is no danger of the work becoming disengaged from the pattern, as it serves to prevent the work from rising under the action of the cutter. The upstanding shaft 78 is preferably provided with a second sleeve 80^a which may be rigidly secured to the shaft 88 in any desired position, and this sleeve serves to determine the position in which the sleeve 80 should be clamped, should the same be raised for any purpose, and it should be desired to return the same to its former position.

When work is first brought into engagement with the cutter there is danger that the rapidly rotating cutter will draw the work inwardly rapidly, with injurious effect, and this is particularly true where a radius cutter is provided which extends over the work a substantial degree, as is the case with the cutters 13 and 24. In the construction shown, the rack 49 and gear 50 insure that the work will be fed smoothly past the cutter after the rack and gear have intermeshed, but the work may be dragged inwardly by the cutter before the gear 50 has engaged the rack, unless means is provided to prevent this. In the present case danger of the work being drawn in by the cutter is avoided by providing either the pattern 30 or the pattern for the cover 73 with an outwardly extending arm 94 adapted to engage the rub roll 46 and prevent movement of the work in the direction in which the cutter rotates. This arm may be disposed in a notch 95 formed in a pattern, and may be pivotally secured in place by a pin 96 (see Fig. 3). A spring 97 is

provided for normally holding the arm 94 in the position shown in Fig. 3, but the arm 94 may swing about its pivot inwardly under a slight pressure to the folded position shown in dotted lines. The arrangement of the arm 94 shown in Fig. 3 is such that after the arm has performed its function and as the work 73 is rotated in a counter-clockwise direction, as indicated by the arrow, the arm will be gradually moved away from the rub roll 46 and when the work has been rotated thru almost a complete circle the opposite side of the arm 94 will engage the opposite side of the rub roll 46, whereupon the arm 94 will be swung about its pivot 96 sufficiently to permit the cutter to act entirely around the cover 73 to complete its cutting operation, and as soon as the arm is moved out of engagement with the rub roll, it will be swung by the spring 97 to its normal operative position, shown in full lines in Fig. 3.

In the present device the electric motors serve to drive the cutters at a high speed, and, since means is provided for automatically holding a pattern against its rub roll, and power means is provided for feeding the work smoothly past the cutter, the present machine will cut satisfactorily against the grain of the wood as well as with the grain, and as a result the cutting operation may be performed entirely around the work by a single cutter.

In the construction so far described the pattern and work are rotated relative to the cutter by a rack that encircles the pattern and meshes with a drive gear 50. This is a good practical construction and permits the pattern and work to be readily removed from and applied to the machine, and this construction serves to feed the work past the cutter at a uniform speed irrespective of its configuration or distance of different parts of the work from a central axis. In some cases it may be desirable to drive the pattern from a central axis so that the speed at which a portion of the work is fed past the cutter will depend upon the distance of the same from the central axis of the pattern, and two different forms of means for driving the pattern through the central axis are shown in Figs. 5, 6 and 7.

In Figs. 5 and 6 the table 12 has the rotating cutter 24 secured to a driving shaft 25 the same as in Fig. 1, and the slide 34 moves toward and from the cutter in a slot 35, as above described, and is urged toward the cutter by the cable 36 provided with the weight 40. The work 98 is placed upon the pattern 99, and if the work has a central opening, as shown in Fig. 6, it may be secured to the pattern by a bolt 100 extending through the clamping bar 101. The pattern 99 is mounted upon a central shaft 102 rotatably mounted in a sleeve 103 secured in

the slide 34, and the pattern rests upon a plate 104 secured to the shaft 102 and may be rigidly secured to the shaft by tightening the clamping nut 105 engaging the threaded upper end of the shaft. The nut 105 is shown as lying within a recess of the pattern so that it will not prevent a piece of flat work such as indicated by 73 in Fig. 3 from being secured to the pattern, in which case the bolt 100 that screws into the upper end of the shaft 102 is omitted.

The means for driving the shaft 102 should be so constructed that it will not interfere with the movement of the slide 34 toward and from the cutter, and to this end the portion of the shaft 102 projecting downwardly from the slide 34 is provided with a worm gear 106 that meshes with a drive screw or worm 107 extending alongside the path of travel of the slide 34. The arrangement is such that the worm gear rolls along the screw 107 as the slide moves along its path of travel. The ends of the screw shaft 107 are journaled in brackets 108, and this shaft is driven from a shaft 109 by the spiral gears 110, 111. The shaft 109 is driven by the usual cone pulley 112. As a result of this construction driving movement will be imparted from the screw shaft 107 to the pattern irrespective of the position of the slide in its slide-way. During the cutting operation the pattern 99 is held by the weight 40 against the rub ring 112 which may rotate within the portion 48 of the table.

It may be desirable to provide the pattern shaft 102 with a clutch for starting and stopping the rotation of the pattern, and to this end the worm wheel 106 is rotatably mounted on the shaft 102, and a clutch element 113 keyed to the shaft 102 may be moved into and out of engagement with a clutch element 114 of the worm gear. The clutch element 113 may be shifted to and from its active position by hand-operated means.

The construction in Fig. 7 differs from that shown in Figs. 5 and 6 in that a sprocket wheel and chain are employed in place of the worm wheel and screw of Figs. 5 and 6. The pattern of Fig. 7 is provided with a central shaft 102 the same as in Figs. 5 and 6 and the lower portion of this shaft is provided with a sprocket wheel 115 that meshes with the sprocket chain 116 passing around the spaced wheels 117. The sprocket chain 116 is driven by a worm wheel 118 that meshes with the worm 119 upon the feed shaft 56. The run of the chain 116, which the sprocket wheel engages, extends parallel to the path of travel of the slide 34 so that the sprocket wheel will remain in engagement with its chain as the slide moves back and forth. When the work rotating means shown in Figs. 5, 6 and 7 is employed,

the pattern is under the positive control of the drive means as the work moves into and out of engagement with the cutter, with the result that the work is prevented from being 5 rotated rapidly by the cutter.

What is claimed is:—

1. In a wood working machine, in combination, a vertical shaft for supporting and rotating a cutter, a pattern to which the 10 work is secured, a pattern guide adjacent the cutter, a slide supported for movement toward and from the cutter, yielding means for urging the slide toward the cutter, a projection between the slide and pattern for 15 holding the work against the cutter, treadle operated means for moving the slide away from the cutter, and means under the control of the treadle means and moving automatically into position to secure the slide in 20 its retracted position.

2. In a wood working machine, in combination, a vertical shaft for supporting and rotating a cutter, a pattern to which the work is secured, a pattern guide adjacent 25 the cutter, a slide supported for movement toward and from the cutter, yielding means for urging the slide toward the cutter, a projection between the slide and pattern for holding the work against the cutter, a 30 treadle operable to retract the slide, and latch means for holding the slide retracted.

3. In a wood working machine, in combination, a vertical shaft for supporting and rotating a cutter, a pattern to which the 35 work is secured, a pattern guide adjacent the cutter, a slide supported for movement toward and from the cutter, yielding means for urging the slide toward the cutter, a projection between the slide and pattern for holding the work against the cutter, and a 40 rocking lever movable into operative engagement with the slide to retract it when moved in one direction and movable out of operative engagement with the slide when 45 moved in the opposite direction.

4. In a wood working machine, in combination, a vertical shaft for supporting and rotating a cutter, a pattern to which the work is secured, a pattern guide adjacent 50 the cutter, a slide supported for movement toward and from the cutter, yielding means for urging the slide toward the cutter, means for imparting the movement of the slide to the pattern to force the work against the cutter, lever actuated means for retracting the slide, a latch for holding the slide retracted, and foot actuated means for releasing 55 the latch.

5. In a wood working machine, in combination, a vertical shaft for supporting and rotating a cutter, a pattern to which the work is secured, a pattern guide adjacent the cutter, a slide supported for movement toward and from the cutter, yielding means 60 for urging the slide toward the cutter, means

for imparting the movement of the slide to the pattern to force the work against the cutter, a treadle operable to retract the slide, a latch for holding the slide retracted, and means actuated by a different movement of the treadle to release the latch. 70

6. In a wood working machine, in combination, a vertical shaft for supporting and rotating a cutter, a pattern to which the work is secured, a pattern guide adjacent 75 the cutter, a slide supported for movement toward and from the cutter and having pawl receiving teeth, yielding means for urging the slide toward the cutter, means for imparting the movement of the slide to the pattern to force the work against the cutter, and a pawl mounted to engage the teeth of the slide and retract the slide when moved in one direction and to release the slide when moved in the opposite direction. 80

7. In a wood working machine, in combination, a vertical shaft for supporting and rotating a cutter, a pattern to which the work is secured, a pattern guide adjacent the cutter, a slide supported for movement toward 90 and from the cutter, yielding means for urging the slide toward the cutter, means for imparting the movement of the slide to the pattern to force the work against the cutter, an arm protruding from the pattern to engage the pattern guide and hold the work from rushing against the cutter and mounted for movement upon the pattern to an inoperative position, and spring means for returning the arm to its operative position. 95

8. In a wood working machine, in combination, a vertical shaft for supporting and rotating a cutter, a pattern to which the work is secured, a pattern guide adjacent the cutter, a slide supported for movement toward 100 and from the cutter, yielding means for urging the slide toward the cutter, means for imparting the movement of the slide to the pattern to force the work against the cutter, an arm mounted within a depression 105 within the pattern and protruding therefrom to engage the pattern guide and hold the work from rushing against the cutter and mounted for movement within the depression to an inoperative position, and spring 110 means for returning the arm to its normal operative position.

9. In a wood working machine, in combination, a rotating cutter, a pattern to which the work is secured, a pattern guide adjacent 115 the cutter, means for supporting the pattern for movement relative to the cutter, an arm protruding from the pattern to engage the pattern guide and hold the work from rushing against the cutter, and means for supporting said arm for movement to an inactive position as an opposite portion of the arm is forced against the pattern guide. 120

10. In a wood working machine, in combination, a rotating cutter, a pattern to which 125

- the work is secured and having a profile guiding surface, a pattern guide adjacent to the cutter and positioned to engage said surface, means for supporting the pattern for rotative movement relative to the cutter and for movement laterally toward and from the cutter, and means for holding the work firmly seated upon its pattern during the cutting operation, comprising a depressor supported in spaced relation to the pattern support and provided with an universal roller that engages the work at a point near the cutter and is adapted to roll freely upon the work when either a rotative or lateral movement is imparted to the latter.
11. In a wood working machine, in combination, a rotating cutter, a pattern to which the work is secured and having a profile guiding surface, a pattern guide adjacent to the cutter and constructed to engage said surface and hold the pattern a predetermined distance from the cutter, means for supporting the pattern for rotative movement relative to the cutter and for movement laterally toward and from the cutter, and yielding means for holding the work firmly seated upon the pattern, comprising a vertically movable plunger supported above the pattern and provided with an universal roller that engages the work at a point near the cutter and is adapted to roll freely upon the work when either a rotative or lateral movement is imparted to the latter.
12. In a wood working machine, in combination, a work supporting table, a rotating cutter, a pattern to which the work is secured and having a profile guiding surface, a pattern guide adjacent to the cutter and constructed to engage said surface and hold the pattern a predetermined distance from the cutter, means for urging the work and pattern toward the cutter and constructed so that they may be rotated relatively to the cutter and moved laterally towards and from the cutter, and means for holding the work and pattern firmly seated upon their respective supports during the cutting operation, comprising an universal roller supported in spaced relation to the table to receive the work and pattern between it and the table and adapted to engage one of them and exert a substantial downward pressure upon the same and also to roll freely upon the same when either a rotative or lateral movement is imparted to the pattern and work.
13. In a wood working machine, in combination, a rotating cutter, a pattern upon which the work is mounted and having a profile guiding surface, a pattern guide constructed to engage said surface and hold the pattern a predetermined distance from the cutter, means for supporting the pattern for rotative movement relative to the cutter and for movement laterally toward and from the cutter, and means for preventing the work from rising during the cutting operation, including an arm supported in spaced relation to the pattern support, a plunger supported by the arm for vertical movement and urged downwardly by spring pressure, and means at the lower end of the plunger for engaging the work and constructed to move freely over the surface of the work when either a rotative or lateral movement is imparted to the latter.
14. In a wood working machine, in combination, a shaft for supporting and rotating a cutter, a pattern to which the work is secured, a slide mounted for movement toward and from the cutter and upon which the pattern is rotatably mounted, a shaft journaled on said slide to rotate the pattern, a worm gear secured to said shaft, a driving screw meshing with the worm gear and extending in the direction in which the slide travels so that the gear remains in mesh with the screw as the slide moves back and forth, and means for driving the screw to rotate the pattern relative to the cutter.
15. In a wood working machine, in combination, a rotating cutter, a pattern to which the work is secured, a slide mounted for movement toward and from the cutter and upon which the pattern is rotatably mounted, a driving shaft for the pattern journaled upon the slide, a toothed wheel in driving engagement with the pattern shaft, and a driving element for the toothed wheel extending in the direction in which the slide travels and constructed so that it will remain in mesh with the toothed wheel to drive the pattern as the slide moves back and forth relative to the element.
16. In a wood working machine, in combination, a rotating cutter, a pattern to which the work is secured, a slide mounted for movement toward and from the cutter, a shaft rigidly secured to the pattern and journaled in said slide, a toothed wheel for driving the pattern shaft, and a driving element for the toothed wheel supported independently of the slide and extending parallel to the path of movement of the slide so that the toothed wheel will remain in operative engagement with the element as the slide moves toward and from the cutter.
17. In a wood working machine, in combination, a rotating cutter, a pattern to which the work is secured, a slide mounted for movement toward and from the cutter, a shaft rigidly secured to the pattern and journaled in said slide, a toothed wheel for driving the pattern shaft, and a driving element for the toothed wheel supported independently of the slide and extending parallel to the path of movement of the slide so that the toothed wheel may roll along the driving element with its teeth in mesh therewith as the slide moves toward and from the cutter.

18. In a wood working machine, in combination, a shaft for supporting and rotating a cutter, a pattern to which the work is secured, a slide mounted for movement toward and from the cutter, a shaft rigidly secured to the pattern and journaled in said slide, a drive shaft supported independently of the slide and extending parallel to the path of travel of the slide, means for driving the last mentioned shaft, and a driving connection between the drive shaft and pattern shaft to operate the latter and constructed to permit the pattern shaft to move lengthwise of the drive shaft without interrupting the driving engagement. 40
19. In a wood working machine, in combination, a rotating cutter, a pattern to which the work is secured, a slide mounted for movement toward and from the cutter, a shaft rigidly secured to the pattern and journaled in said slide, a toothed wheel for driving the pattern shaft, a driving element supported independently of the slide and extending in the direction in which the slide travels so that the toothed wheel will remain in operative engagement with the driving element as the slide moves toward and from the cutter, and a clutch cooperating with the pattern shaft to start and stop the rotation of the pattern. 45
20. In a wood working machine, in combination, a rotating cutter, a pattern to which the work is secured, a slide mounted for movement toward and from the cutter and upon which the pattern is mounted for rotation past the cutter, a shaft supported by the slide to rotate the pattern, a tooth wheel secured to the shaft to drive it, and driving means for the toothed wheel supported independently of the slide and extending parallel to the path of movement of the slide so that the toothed wheel will remain in operative engagement with the driving element as the slide moves towards and from the cutter. 50
21. In a wood working machine, in combination, a rotating cutter, a pattern to which the work is secured and having a profile guiding surface, a pattern guide adjacent the cutter and constructed to engage said surface and hold the pattern spaced from the cutter, a slide mounted for movement toward and from the cutter, a shaft rigidly secured to the pattern and journaled on said slide, a toothed wheel for turning said shaft to rotate the pattern, and a driving element supported independently of the slide and extending parallel to the path of movement of the slide so that the toothed wheel will remain in operative engagement with the element as the slide moves towards and from the cutter. 55
22. In a wood working machine, in combination, a rotating cutter, a work support, a slide mounted for moving toward and from the cutter, a shaft rigidly secured to the work support and journaled on said slide, a toothed wheel for driving said shaft to rotate the work support, and a driving element for the toothed wheel supported independently of the slide and extending parallel to the path of movement of the slide so that the toothed wheel will remain in operative engagement with the driving element as the slide moves towards and from the cutter. 60

In testimony whereof, I have signed my name to this specification.

WILLARD N. SAWYER.
